CHARLES I. MCNEIL, OF BLOOMFIELD, NEW JERSEY, ASSIGNOR TO ECLIPSE MACHINE COMPANY, OF ELMIRA HEIGHTS, NEW YORK, A CORPORATION OF NEW YORK

CONTROLLING GENERATOR

Application filed January 16, 1929. Serial No. 332,998.

REISSUED

This invention relates to controlling or regulating the output of an electric current generator.

It has heretofore been proposed to employ a regulator of the vibrating reed or armature type for controlling the output, such as the voltage output, of a generator. Regulators of this type embody a pair of contacts which are opened and closed by an electromagnet for purposes well understood in the art, the opening and closing movements of the contacts being usually of the order of 10 to 40 cycles per second. When regulators of this type are employed for controlling the voltage output of a generator used in radio transmitting apparatus of the continuous-wave type the action of the contacts results in an intermittent note in the receiver so similar in pitch to that of other sounds in the transmitted waves as to render impossible, in many instances, the satisfactory reception of signals. Accordingly, one of the objects of the present invention is to provide novel regulating means of the vibratory type which is so constituted as to overcome the above objectionable effect.

Another object of the invention is to provide a novel regulator embodying a pair of coacting contacts for intermittently interrupting an electric circuit and means for rendering the action of said contacts of relatively high frequency such, for example, as 80 to 300 or more cycles per second.

Another object is to provide a novel method for controlling the frequency of opening and closing of a pair of coacting contacts of the character above indicated. For claims to this novel method reference is to be had to applicant's co-pending application Serial No. 618,783, filed June 22, 1932, the claims herein being directed only to certain forms of apparatus for carrying said novel method into effect.

Another object is to provide a novel regulator embodying an electromagnet provided with a plurality of coils or windings of such character that the make-and-break action of the contacts is of relatively high frequency.

A further object is to provide a regulator embodying a multi-coil electromagnet, the

various coils being so formed and combined as to insure proper regulation regardless of changes in speed of and load on the generator.

Another object is to provide a novel voltage regulator of the vibrating armature type which is particularly adapted for use in radio transmitting apparatus. The above and other objects will appear more fully hereafter in the detailed description.

Two embodiments of the invention are illustrated in the accompanying drawings, but it is to be expressly understood that the drawings are for purposes of illustration only and are not designed as a definition of the limits of the invention, reference being had for this purpose to the appended claims.

In the drawing:

Fig. 1 is a diagrammatical view illustrating one form of regulating apparatus embodying the present invention; and

Fig. 2 is a diagrammatical view of another embodiment of the invention.

Referring more particularly to Fig. 1 the armature of the generator to be regulated is indicated at 3, the field winding at 4, and the field resistance at 5, said winding and resistance being connected in series across the positive main 6 and the negative main 7.

The novel regulating means comprises a pair of contacts 8 and 9 which are normally closed and are shunted around the resistance 5. Contact 9 is mounted on a vibrating armature 10 which is pivotally mounted in any suitable manner, and adjustable resilient means such as a coil spring 11 is operatively connected to said armature to normally maintain contact 9 in engagement with contact 8.

An electromagnet having a core 12, which is preferably laminated, is associated with armature 10, and spring 11 is so adjusted that when the voltage of the generator rises above a predetermined value the electromagnet is effective to overcome the tension of said spring and move contact 9 out of engagement with contact 8, whereupon the field resistance 5 is placed in circuit with the field 4. The resistance of the field circuit is now of such value as to prevent the desired amount of field current from flowing, whereupon a reduction in the generator voltage is produced.

This dropping of the voltage weakens the magnetic field of the electromagnet to such an extent that the contacts 8 and 9 are closed by spring 11 to short circuit resistance 5, 5 whereupon the field flux and armature voltage are again built up.

The core 12 of the electromagnet carries a winding 13 which is in series with a resistance 14, the winding and resistance being 10 connected across the mains 6 and 7 in parallel with contacts 8, 9. The magnetic field set up by parallel coil 13 rises or falls relatively slowly, since it varies in accordance with the changes in the voltage in the armature. The 15 latter in turn follows the changes of current in the field. Accordingly, in regulators embodying only a coil such as is indicated at 13 the opening and closing movements of contacts 8 and 9 are relatively slow, i. e., they are 20 of the order of 10 to 40 cycles per second.

In accordance with the present invention means are provided for speeding up the action of the contacts, whereby the movement of the same is of a high frequency as, for 25 example, 80 to 300 or more cycles per second. For this purpose the core 12 carries a second winding 15 which is connected in series with a resistance 16, said winding and resistance being shunted around generator field 4 and 30 in series with contacts 8 and 9. Coil 15 is wound in such a manner as to strengthen the magnetic field set up in core 12 by the coil 13, and the tension of spring 11 is overcome only when both coils coact to produce the 35 desired strength of field.

When the contacts are closed current flows from the positive main 6 through said contacts, series coil 15, and resistance 16, and said series coil coacts with parallel coil 13 40 to set up the magnetic field in core 12. When the voltage output of the generator exceeds a predetermined amount as determined by the setting of spring 11, the magnetic field of the electromagnet is sufficiently strong, due to 45 the combined action of coils 13 and 15, to overcome the tension of spring 11 and move contact 9 out of engagement with contact 8. The instant the contacts open the current in series coil 15 falls, thus producing a sudden 50 drop in the flux of core 12 and this drop is independent of the fall of the voltage in the armature 3. Armature 10 instantly moves to reengage contact 9 with contact 8, due to the action of spring 11. A much quicker action 55 of the contacts is thus obtained than results from the use of a single coil such as parallel coil 13 since the magnetic field produced by the latter falls relatively slowly in accordance with the drop of voltage in the armature.

60 The use of series coil 15 in combination with parallel coil 13 is sufficient to raise the frequency of the contacts to as high as 80 to 300 cycles or more per second. This change 65 in the frequency of the contacts may not entirely eliminate the intermittent note result-

ing from the engagement and disengagement of the contacts, but the note will be of a much higher pitch than that of other sounds resulting from the transmitted waves and hence will not interfere with the reception of the signals. In other words, the regulator of 70 the present invention is so constructed as to eliminate or minimize the interference or noises in radio signals emitted by a transmitter energized by a voltage regulated generator. 75

The resistance units 14 and 16 may be employed as indicated in order to permit the use of a larger current flow in coils 13 and 15 without danger of overheating the coils as 80 might result from winding the resistances directly on core 12. The larger portion of the heat is generated in the resistance and by placing said resistance at a distance from the coil a greater flow of current may be used 85 for a predetermined coil temperature. Since the circuit 15, 16 is of small inductance it acts to absorb a portion of the voltage set up in field 4 by the sudden changes in field current. 90

It is highly desirable that the regulator maintain the voltage constant within very narrow limits. Since the current in series coil 15 varies in proportion to the field current, which latter in turn varies with the speed of and the load on the generator, a change in the current flowing through said coil results in a slight change in the setting 95 of the regulator.

Conversely, on decrease in the effective 100 value of the field current (such as results from an increase in generator speed or a decrease in load) the voltage impressed upon coil 15 decreases, thereby weakening the magnetic pull. To offset this decrease in pull, coil 13 must be strengthened by increase in voltage from the generator in order to effect 105 opening of contacts 8 and 9. Thus there is a tendency for the generator voltage to rise with increase in speed or removal of load. This tendency may be overcome, or at least 110 compensated for by the use of the arrangement shown in Fig. 2, now to be described.

In Fig. 2 there is illustrated another embodiment of the present invention wherein a change in the current flowing through coil 15 is ineffective to vary the regulator setting. For this purpose the core 17 of the electromagnet carries a third coil 18 in series with a resistance 19, said coil and resistance being 115 in parallel with contacts 8 and 9 and also in series with coil 15. When the contacts are open, the current flowing through coil 18 is relatively high and the current flowing through coil 15 is relatively low, and the field set up by coil 18 is acting in a direction opposite to that set up in coil 15. When the contacts are closed, substantially no current flows through coil 18 while a relatively large 120 amount of current flows through coil 15, and, 125

as pointed out above in connection with Fig. 1, the coils 15 and 13 coact together to set up the desired magnetic field for opening contacts 8 and 9.

5 As the voltage tends to rise above the desired amount, a point is reached where the field set up by coils 13 and 15 is effective to overcome the tension of spring 11 and open contacts 8 and 9. Immediately the field of 10 coil 15 drops due to the decrease in current now flowing through this coil while a relatively large amount of current flows through coil 18, and the field of the latter is effective to diminish or nullify the effect of the field 15 in coils 13 and 15. In other words, the magnetic field for holding the contacts open is very quickly destroyed and spring 11 is now effective without any delay to again close the contacts. Hence the speed of the regulator 20 is increased by the use of coil 18.

This increase is further accelerated as the speed of the generator increases, because the current in coil 18 varies as the voltage across the contacts 8 and 9, which in turn varies inversely with the speed of the generator. Hence, at high speeds, (or upon removal of load) demagnetizing force of coil 18 is increased thereby causing contacts to close sooner than at low speeds or at relatively 30 high loads.

From the foregoing it is apparent that the addition of the coil 18 serves to increase the speed of contact operation and compensate for any tendency in the system toward a 35 variation in voltage across the lines 6 and 7, the ultimate result being an improvement in the quality of regulation.

There is thus provided a novel regulator which is simple in construction and which 40 may be satisfactorily employed in radio transmitting apparatus for maintaining constant voltage. It is to be expressly understood, however, that the regulator is not limited in its use to the radio field, as will now 45 be readily apparent to those skilled in the art, and reference will be had to the appended claims for a definition of the limits of the invention.

What is claimed is:

50 1. In combination with a generator having a field winding and a field resistance, means for regulating the voltage output of said generator by intermittently placing said resistance in circuit with said field winding 55 including a pair of coacting contacts, and means including an electromagnet for controlling the engagement of said contacts, the electromagnet embodying a coil in series with said contacts and in parallel with said winding and another coil in parallel with said contacts.

60 2. In a regulator of the type embodying a pair of coacting contacts, a pivoted armature carrying one of said contacts, yielding means 65 for maintaining said contacts closed, and an

electromagnet for opening said contacts, the electromagnet including a core and a plurality of coils wound thereon, one of the latter being in series with said contacts and another of the same being in parallel with the 70 contacts but in series with the first named coil, and a third coil in parallel with the first.

3. In a regulator of the type having a vibrating armature, an electromagnet comprising a core, a coil on said core having a 75 series relationship with said armature and two other coils on said core, the series coil being adapted to coact with one of said other coils to set up a predetermined field in said core and being adapted to coact with the 80 third coil to compensate for changes in the field induced by said third coil.

4. In a regulator of the vibrating armature type, an electromagnet comprising a core, and a plurality of coils wound thereon, the first 85 and second of said coils being adapted to coact one with the other to set up a predetermined field in said core, and a third coil adapted to coact with said first and second coils, and the first named coil being also 90 adapted to compensate for the changes in the magnetic field resulting from said third coil.

In testimony whereof I have signed this specification.
